UNITED STATES PATENT OFFICE

132,891

DESIGN FOR A TOOL HANDLE

David Chapman, Chicago, Ill., assignor to Snap-On Tools Corporation, Kenosha, Wis.

Application February 3, 1941, Serial No. 98,665

Term of patent 7 years

To all whom it may concern:

Be it known that I, David Chapman, a citizen of the United States and a resident of Chicago, county of Cook, and State of Illinois, have invented a new, original, and ornamental Design for a Tool Handle, of which the following is a specification, reference being had to the accompanying drawing forming part thereof.

In the drawing:

Figure 1 is a top plan view of a tool handle showing my new design.

Figure 2 is an end view thereof.

Figure 3 is a cross-sectional view thereof taken through the handle and looking toward the grip portion.

Figure 4 is a perspective view thereof.

I claim:

The ornamental design for a tool handle, substantially as shown.

DAVID CHAPMAN.
